(57) **CLAIM**

The ornamental design for a wall mounted LED area light, as shown and described.

DESCRIPTION

FIG. 1 is a perspective view of the wall mounted LED area light showing the new design;

FIG. 2 is a side elevation view thereof with the opposite side being a mirror image of that shown;

FIG. 3 is a top plan view thereof;

FIG. 4 is a front elevation view thereof;

FIG. 5 is a rear elevation view thereof; and,

FIG. 6 is a bottom plan view thereof.

The broken lines shown on the drawings represent portions of the light that form no part of the claimed design.
